UNITED STATES PATENT OFFICE.

JOHN W. GAUNT, OF SOUTH HADLEY, MASSACHUSETTS.

DESIGN FOR A MATCH-SCRATCHER.

45,706.

Specification for Design.

Patented May 5, 1914.

Application filed March 3, 1914. Serial No. 822,237. Term of patent 14 years.

To all whom it may concern:

Be it known that I, JOHN W. GAUNT, a subject of the King of Great Britain, residing at South Hadley, in the county of Hampshire and State of Massachusetts, have invented a new, original, and ornamental Design for Match-Scratchers, of which the following is a specification, reference being had to the accompanying drawing, forming part thereof.

Figure 1 is a plan view, showing my new design, and Fig. 2 is a sectional view taken on the line 2—2 of Fig. 1, looking in the direction indicated by the arrows.

I claim:

The ornamental design for a match scratcher, as shown.

JOHN W. GAUNT.
